UNITED STATES PATENT OFFICE.

JAMES W. PATTERSON, OF WHITE PLAINS, NEW YORK, ASSIGNOR TO AUTOSALES GUM AND CHOCOLATE COMPANY, OF NEW YORK, N. Y., A CORPORATION OF NEW YORK.

COIN-OPERATED VENDING-MACHINE.

1,153,440.

Specification of Letters Patent. Patented Sept. 14, 1915.

Application filed August 22, 1912. Serial No. 716,411.

To all whom it may concern:

Be it known that I, JAMES W. PATTERSON, a citizen of the United States, and a resident of the village of White Plains, county 5 of Westchester, and State of New York, have invented certain new and useful Improvements in Coin-Operated Vending-Machines, of which the following is a specification.

10 My invention relates to coin-operated vending machines of the so-called magazine type in which the vendible articles are stacked in magazines to be ejected one at a time at each operation of the machine.

15 The object of my invention is to provide a vending machine of this class, having two compartments or magazines and two independent ejecting mechanisms, one for each magazine, adapted to be operated through

20 the medium of a coin held on a common hand-operated coin-carrier. This coin-carrier is freely movable in opposite directions and is normally disconnected from both of the ejected mechanisms. However, when a

25 coin is deposited in the coin-entrance slot of the machine, it finds support on the carrier which, upon operation in one direction or the other, moves the coin into engagement with one or the other of the ejected mechanisms and actuates the same to eject a package of goods from the associated magazine.

30 The operation of either ejecting mechanism has no effect upon the other. In this way the purchaser may select from which compartment the goods shall be ejected, by simply manipulating the common coin-carrier in one direction or the other.

35 Considered in its broad aspect, the principle of my invention may be mechanically carried out in different ways and for the sake of illustration I have shown one specific form of my invention in the accompanying drawings in which:

40 Figure 1 shows a front elevation; Fig. 2 is a vertical cross section substantially on line 2—2 of Fig. 1; Fig. 3 is a fragmentary view in elevation showing the coin-controlled mechanism; Fig. 4, is a vertical cross section substantially on line 4—4 of Fig. 3; Fig. 5 shows a cross section, on an enlarged scale, on line 5—5 of Fig. 4; and Fig. 6 is a cross-sectional plan view substantially on line 6—6 of Fig. 3.

The various operative parts of the ma-

chine are housed in a suitable casing, comprising the base 1, the back 2, the front 3, the top 4 and the sides 5. If desired the back 2 may be hinged to the base at 6 so that ready access may be had into the interior of the casing. A suitable lock 7 is provided for locking the back 2 in closed position. The front 3 is preferably of glass or other transparent material, so that the vendible goods may be exposed to view. The front 3 terminates at the bottom at 8, so as to leave 65 the discharge opening 9 for the ejected articles.

The machine is provided with two magazines in which the vendible articles are supported in vertical stacks. These magazines 70 may be formed in any suitable way. In the specific embodiment shown in the drawings, each magazine comprises four upright angle bars 10, which are secured to the top and base of the casing by screws 11 passing 75 through the horizontal flanges 12 of the angle bars. The lowermost article in each magazine rests upon plates 13 carried by each pair of front and rear angle bars, as shown in Figs. 5 and 6. The front bars 10 80 of each magazine are provided with a pair of extensions 14 which carry at their free ends the transverse guide 15, for deflecting the article toward the discharge opening 9.

As previously stated, with each magazine 85 is associated an independent ejecting mechanism. As these mechanisms are identical in construction and operation, a detailed description of one will be sufficient for both. Beneath the supporting plate 13 each magazine is provided with a pair of inwardly extending brackets 16 which are rigidly mounted on the angle bars by screws or bolts 17. Between each pair of brackets is slidably mounted the ejector 18, which is at the 95 rear end provided with a forwardly extending ejecting finger 19. The brackets 16 are at their adjacent edges provided with slots 20 in which the ejector slide 18 engages. The free end of the ejecting finger 19 is so 100 arranged that when the ejector slide is drawn forwardly the finger engages the lowermost package at the rear end and pushes the same out of the magazine.

In each pair of brackets is journaled a 105 shaft 21, on which is fixed the gear 22. This gear is arranged to be permanently in mesh with the teeth 23 of the ejector

slide 18, so that the rotation of the shaft 21 always causes reciprocation of the ejector slide. At its inner end the shaft 21 carries the pinion 24 which is rigidly fixed upon the shaft in any suitable way. In Fig. 5 the pinion 24 is shown as being provided with a sleeve 25 which is keyed to the shaft by means of a pin 26. Between the two magazines is interposed an upright frame 27, which is provided with a pair of slotted guide strips 28. In the slot 29 of each guide strip is mounted the slide 30 provided with the rack 31, which is arranged to be permanently in mesh with the associated pinion 24. The contractile spring 32, secured at its lowermost end of the hook 33 of the rack 31 and at its upper end to the lug 34 carried by the guide strip 28, normally holds the rack 31 in its uppermost position, as shown in Figs. 4 and 5. The frame 27, is formed with a slotted or recessed portion which provides the coin-entrance slot 35, the coin-exit slot 36, and the intermediate chamber 37 for receiving the coin-carrier 38. A plate 39 secured to the front of the frame 27 by screws 40 or otherwise, forms the front wall of the recessed portion in the frame 27. The coin-carrier 38 comprises a disk having a pair of diametrically opposite recesses 41 for receiving the deposited coins 42, as best shown in Fig. 3. The coin-carrier 38 is operated from the outside of the casing by means of a knob 43 fixed on the outer end of the shaft 44, which carries at its inner end the coin-carrier. The shaft 44 is supported by the front panel 3 and the plate 39. Each of the slides 30 is provided with a stud or lug 45, which extends into the chamber 37. The frame 27 is provided with a pair of swinging pawls 46, arranged over the lugs 45 and adapted to be deflected by the coin-carrier. The latter is at all times out of contact with the slides 30, which may properly be considered as parts of the ejecting mechanisms.

The operation of my machine will be clear from the foregoing description, and may be stated as follows: When the coin is deposited in the entrance-slot 35 through the coin-slot provided in the plate 48, on the top of the casing, it drops on to the coin-carrier 38. Should the latter be in the position shown in Fig. 3, the deposited coin 42 at once falls into the upper recess 41. Should the recess 41 happen to be out of alignment with the slot 35, the coin will fall upon the periphery to the coin-carrier, and will automatically drop into one of the recesses as the coin-carrier is rotated. Should the purchaser desire a package of goods from the right-hand magazine, he turns the knob 43 toward the right, thereby carrying the coin against the stud 45 of the right-hand slide 30. The coin is held between the coin-carrier and the side wall of the cham-

ber 37, and as soon as it engages the stud 45, it forces the slide 30 downwardly. This causes the shaft 21 to rotate counterclockwise (as viewed in Figs. 2 and 4), whereby the ejector slide 18 is moved forwardly, causing the finger 19 to push the lowermost packages of goods out of the magazine. When the lowermost article is projected forwardly, the front end temporarily rests upon the transverse guide lip 15, so that the article is tilted downwardly at its rear end as soon as the ejector slide 18 retreats from under the ejected package. As the article drops it falls upon the curved deflector 49 and slides down the same through the discharge opening 9 within easy reach of the purchaser. The deflector 49 may conveniently be secured to the front angle bars 10 by screws 50 or otherwise. As the article is ejected it passes under the dogs 51 hinged at 52 to the front angle bars 10, and after it has advanced sufficiently these dogs drop back to prevent the article from accidentally moving backward. This positively prevents interference with the descent of the next package or article of goods. As soon as the coin 42 has passed the pivoted pawl 46, the latter drops back into normal position and prevents reverse movement of the coin-carrier before the completion of the forward movement. The transmission ratios of the gear connections between the slide 30 and the ejector 18 are such that the movement of the slide through the medium of the deposited coin is of sufficient extent to cause complete ejection of the article from the magazine by the ejecting finger 19. After the coin has fully depressed the slide 30, it passes out of engagement with the lug 45 and drops through the coin-exit slot 36 to the bottom of the casing behind the deflector 49. If the purchaser desires a package of goods from the left-hand magazine, he rotates the knob 43 toward the left, whereby the left-hand ejector mechanism is operated in the same manner as the right-hand ejecting mechanism. It will thus be seen that a single coin-carrier may be operated at will to produce the discharge of the articles from either of the compartments.

While I have herein shown and described a specific construction embodying my invention, I would have it understood that this is merely for the sake of illustration and not by way of limitation. It is obvious that many changes in details may be made by those skilled in the art without departing from the scope of the invention as defined in the appended claims. For instance, the ejecting member may assume various constructions, and the operative connections between the ejecting member and the coin-actuated lugs 45 may be effected in other ways than that shown in the drawing.

Having thus described my invention, what

I claim as new and desire to secure by Letters Patent, is:

1. In a coin-operated vending machine, a casing provided with two compartments for holding the vendible articles in stacks, an independent ejecting device associated with each compartment and movable for ejecting the articles therefrom, each of said devices being automatically positioned after every operation thereof to eject the next article from the associated magazine, and a single hand-operated coin-carrier normally disconnected from both of said devices and adapted to be freely actuated in opposite directions for connection with either of said devices through the medium of the coin on said carrier. 70
2. In a coin-operated vending machine, the combination of a casing provided with two compartments for holding the vendible articles in stacks, an independent ejecting mechanism associated with each compartment and having means arranged below the compartment to eject the lowermost article horizontally therefrom, and a single hand-operated coin-carrier normally disconnected from both of said mechanisms and adapted to be freely actuated in opposite directions for connection with either of said mechanisms through the medium of the deposited coin on said carrier. 80
3. In a coin-operated vending machine, the combination of a casing provided with two compartments for holding the vendible articles in stacks, an independent ejecting mechanism associated with each compartment and having a horizontally slidable member arranged below the compartment to eject the lowermost article horizontally therefrom, and a single hand-operated coin-carrier normally disconnected from both of said mechanisms and adapted to be freely actuated in opposite directions for connection with either of said mechanisms through the medium of the deposited coin on said carrier. 90
4. In a coin-operated vending machine, the combination of a pair of independent ejecting mechanisms having each a member to engage and eject the vendible articles, and a single device normally disconnected from both of said mechanisms and adapted to be manually operated in opposite directions for selective connection with either of said mechanisms through the medium of the deposited coin, whereby either ejecting member may be operated. 100
5. In a coin-operated vending machine having two compartments for holding the vendible articles in vertical stacks, the combination of a pair of independently movable elements, a coin-carrier rotatable between said elements and normally disconnected therefrom, said carrier being adapted to carry the coin into engagement with one or the other of said elements and thereby operate the same, an ejecting member associated with each compartment for ejecting the articles horizontally therefrom, and independent operative connections between said elements and said ejecting members. 110
6. In a coin-operated vending machine having two compartments for holding the vendible articles in stacks, the combination of two independently reciprocable slides, an ejector associated with each compartment for ejecting the articles therefrom, independent means for connecting each of said ejectors with one of said slides, a rotatable coin-carrier arranged to operate between said slides, a projection on each slide arranged in the path of movement of the coin on the carrier, so that when the carrier is rotated in one direction the coin acts upon the projection of one slide, while reverse rotation of the coin-carrier causes the coin to act upon the projection of the other slide, and means on the outside of the machine for manually operating said coin-carrier. 120
7. In a coin-operated vending machine, a casing having two compartments for holding the vendible articles in stacks, independent mechanism associated with each compartment for ejecting the articles therefrom, means whereby each of said mechanisms is automatically positioned after every operation thereof to eject the next article from the associated magazine, a hand-operated member adapted to receive the deposited coins and normally out of operative connection with both of said mechanisms, said member being mounted mid-way of said magazines and at all times freely operable in opposite directions toward one magazine or the other to carry the deposited coin into contact with either of said mechanisms for operating the same, and a coin guide or passage for directing the deposited coin into position on said hand-operated member. 130
8. In a coin-operated vending machine, a casing having two compartments for holding the vendible articles in stacks, independent mechanism associated with each compartment and having means to eject the articles therefrom, a single hand-operable member common to both of said mechanisms and at all times out of contact therewith, said member being adapted to receive the deposited coin and freely operable in opposite directions to actuate one or the other of said mechanisms through the medium of the deposited coin, such mechanisms having portions extending on opposite sides of said member and adapted to be engaged by the coin thereon. 140
9. In a coin-operated vending machine, a casing provided with two compartments for holding the vendible articles in stacks, a pair of independently movable members adapted to be engaged by the deposited coin 150

and thereby operated, a single coin-carrier mounted to operate between said members and freely rotatable in opposite directions to carry the deposited coin into engagement with one or the other of said members, an independent ejecting mechanism associated with each compartment, and operative connections between each of said ejecting mechanisms and the corresponding coin-actuated member.

10. In a coin-operated vending machine, the combination of a casing provided with two compartments for holding the vendible articles in stacks, an independent ejecting mechanism associated with each compartment, a single hand-operated coin-carrier normally disconnected from both of said mechanisms and adapted to be freely actuated in opposite directions for connection with either of said mechanisms through the medium of the deposited coin on the carrier, and means for automatically returning each of said ejecting mechanisms to normal position after every operation thereof, so that said mechanisms may each be operated repeatedly without manual resetting to eject the articles one by one from said magazines.

11. In a coin-operated vending machine, a pair of horizontally slidable ejectors movable independently of each other, a pair of vertically slidable members mounted independently of each other and each connected with one of said ejectors, and a rotatable element mounted between said members and at all times freely rotatable in opposite directions to carry the deposited coin into engagement with one or the other of said members to actuate the same and thereby operate the connected ejector.

12. In a coin-controlled mechanism, the combination of a plurality of independently operable shafts, an actuating member connected with each shaft, and a single hand-operated coin-carrier normally disconnected from all of said members and adapted to be operated for selective connection with either of said members to cause actuation of the connected shaft.

13. In a coin-controlled mechanism, the combination of a pair of horizontal shafts operable independently of each other, a vertically slidable member operatively connected with each shaft, and means for carrying a deposited coin into engagement with either of said members to actuate the same and thereby operate the connected shaft, said means at all times being out of engagement with said members.

14. In a coin-operated vending machine, a casing provided with two magazines for containing the vendible articles, a pair of re-

ciprocating slides for respectively controlling the discharge of the articles from said magazines, a projection on each of said slides, a coin-passage arranged between said slides, a rotatable disk mounted to operate in said coin-passage for receiving the deposited coin, said disk being freely rotatable in opposite directions to move the coin into engagement with the projection of one slide or the other, and means extending from said disk to the outside of the casing for manually operating said disk.

15. In a coin-operated vending machine, a plurality of compartments for containing the articles to be vended, mechanism for each of said compartments for directly causing the articles to be discharged therefrom successively, a hand-operated part adapted to receive and move the deposited coin and arranged out of operative connection with said mechanisms, and a coin-guide for guiding a coin to said hand-operated part and permitting said coin to be moved thereby into contact with either of said mechanisms and operate same for discharging the articles.

16. In a coin-operated vending machine, a casing provided with a plurality of compartments for holding the vendible articles, devices for separately discharging the articles from the respective compartments and wholly inclosed within said casing, a coin-guide within said casing having a plurality of passages leading to said devices, a rotary part adapted to receive a deposited coin and move it into either of said coin passages into contact with the associated device for causing the discharge of the desired articles, and a hand-operated member extending from the outside of the casing to said coin-receiving part for operating the same.

17. In a coin-operated vending machine, a casing provided with a pair of compartments for containing the vendible articles, independent self-resetting mechanism associated with each compartment for ejecting the articles therefrom, a single hand-operable device arranged at the front of said casing and extending through the front wall to the interior thereof, said device being freely movable in opposite directions and provided with a coin-moving part for moving the coin into contact with either of said mechanisms, and means for guiding the deposited coins to said coin-moving part.

In witness whereof, I hereunto subscribe my name this 9 day of August A. D., 1912.

JAMES W. PATTERSON.
